UNITED STATES PATENT OFFICE.

RICHARD E. KLINE, OF LOS ANGELES, CALIFORNIA.

CROWN-BLOCK.

1,108,078.

Specification of Letters Patent. Patented Aug. 18, 1914.

Application filed January 10, 1913. Serial No. 741,160.

To all whom it may concern:

Be it known that I, RICHARD E. KLINE, a citizen of the United States, residing at Los Angeles, in the county of Los Angeles, State 5 of California, have invented new and useful Improvements in Crown-Blocks, of which the following is a specification.

This invention relates to crown blocks for oil well drilling rigs and the like; and the 10 invention has for its prime immediate object the provision of a simple and efficient crown block, amply strong to withstand all of the severe strains to which crown blocks are subjected, and durable as to wearing 15 faces.

There are several features of my improved crown block which I may especially mention as follows; first, the complete and substantial rigidity of the whole structure; 20 second, the substantial bearing construction for the different sheaves so as to reduce friction and wear; third, dust proof construction and automatic oiling devices for all of the bearings; and fourth, adjustability of the different sheaves in their positions relative to one another and on the block framing.

Incorporating as it does the above mentioned features, my block at once fulfills the 30 most rigid requirements of devices of this character. It is particularly useful that the boxes or bearings be constructed dust proof and with automatic oilers; thus obviating constant care of the bearings, which 35 are more or less difficult of access at the top of the drilling derrick.

Other features of this invention will become more readily apparent from the following specification, taken in connection 40 with the accompanying drawings in which I have shown various views of a preferred form of my crown block, as follows:

Figure 1 is a side elevation of an approved form of my crown block. Fig. 2 is a plan 45 view of the same. Fig. 3 is an enlarged section taken on line 3—3 of Fig. 2. Fig. 4 is a section taken on line 4—4 of Fig. 3.

The frame of my improved crown block is made essentially of a number of longitudinal I-beam members 10 and 11, members 50 10 being preferably shorter than the members 11 for the reason that the members 11 are designed to support between them the sand line sheave 12 whose outer edge hangs 55 over the outer edge of the derrick crown. The frame members 10 are spaced apart by suitable plates 13, 14 and 15, these plates

being fitted between the I-beams as is best shown in Figs. 1 and 2. Heavy bolts 16, 17 and 18 extend through the various beams 60 and secure them rigidly together; the combined effect of the whole construction being to prevent any twisting motion of any beam or of the entire structure. It is seen in Figs. 1 and 2 that the bolts 16 preferably extend 65 through the complete structure; and that the plates 13 are all in alinement with each other; while at the outer end of the block, the plate 15 and bolt 18 are situated at the ends of the longer members 11 and the 70 plates 14 and bolts 17 are situated some distance inside the ends of the shorter members 10. This arrangement is made particularly to accommodate the sand line 75 sheave 12.

I provide four or more sheaves 20, commonly known as casing sheaves, these being the sheaves over which the cable is reaved for heavy pulling on casing. The sheaves 20 are arranged symmetrically about the center of the block; so that, when the block is placed on the crown of a derrick, the sheaves will be arranged symmetrically with relation to the hole beneath. (The hole may or may not be in the center of the derrick; and the 80 sheaves will be placed on the derrick crown in conformance with the position of the hole with respect to the derrick.) Each of the casing sheaves 20 is mounted in a pair of bearings 21 adjustably placed upon the 90 longitudinal I-beam members 10 and 11. Each of these bearings 21 has base bolts 22 which pass through suitable apertures 23 in the frame members 10 and 11; and there are provided extra holes 23 so that the bearings 95 may be moved along the I-beam members to properly adjust the position of the sheave. This adjustment provides for adaptation of the sheaves to any position of the hole with respect to the derrick, allowing the block to be properly centrally 100 located upon the derrick crown.

The sand line sheave 12 is mounted in suitable bearings 25 which are adjustable on the longitudinal beams 11 in the same 105 manner as before described. The main line, or drilling line, sheave 30 is mounted in bearings 31; and it will be noted that a pair of the bearings 21 and the bearings 31 are constructed together; so that the sheaves 30 110 may be placed in about the position shown relative to the sheaves 20 carried by these bearings 21. When the sheaves are adjusted longitudinally of the beams they main-

tain their proper relative relation to each other. All of the bearings 21 of all of the sheaves 20 are duplicates of each other with the exception of these bearings 21 which are formed together with the bearings 31. The internal constructions and arrangements of the different bearings are all the same; and I have shown details of the bearings 21 and 31, these details illustrating not only the internal construction of all the bearings but showing also the peculiar connective construction of these two bearings.

The sheaves 20 have hollow trunnions 35, the interior bores of the trunnions being tapered with their small diameters at the center of the trunnion. This construction at once gives the greatest possible strength with the least possible weight, and also provides the greatest strength at the point where it is the most needed. Sheaves 20 are made more heavily and with heavier trunnions and bearings than any of the other sheaves on the crown block. The main line sheave 30 is provided with a smaller solid trunnion 36 which is supported in the bearings 31. The lower halves of these bearings are carried in the base block 37 which has oil reservoirs 38 to carry a sufficient amount of lubricating oil to supply the bearings for a long time. The lower halves of the bearings are provided with suitable bearing sleeves of antifriction metal 39, constructed in halves so as to allow the passage of oil rings 40 to carry the oil to keep the trunnions and bearings constantly lubricated. The upper halves of the bearings are not provided with any bearing sleeves, the trunnions 35 and 36 resting in the bearing sleeves 39 and all the strain being downwardly. And this construction facilitates the distribution of lubricant over the upper side of the trunnion, so that the lubricating oil is thoroughly distributed over the trunnion where it passes into the bearing sleeve 39.

The upper halves of all the bearings are constructed as shown in Figs. 3 and 4. They each consist in a main trunnion covering portion or cap 45 secured on the lower bearing half by means of suitable bolts 46. The upper bearing half or cap not only covers the upper periphery of the trunnion but also has a flat circular cap which covers the end of the bearing and the end of the trunnion and prevents entry of dust to the bearing. This is an important feature, especially in connection with the self-oiling feature of the bearing; and these two features, together, obviate all necessity for constant attention to the crown block. The oil rings 40 pass over the trunnions in the ordinary manner, and the upper bearing half or cap has a suitable semi-circular groove 47 for its accommodation; having an oil cup 48

with a cover 49 for the purpose of filling the bearing with oil.

To prevent entry of dust, which might otherwise settle into the space between the inner edge or end of the bearing cap and the shoulder 20^a on the wheel trunnion, I have provided a suitable dust strip 50 which is attached to the bearing cap and overlaps the enlarged portion of the trunnion or of the sheave. (I have shown the dust strip in Fig. 4 and as applied to one bearing in Fig. 2; this for clarity of illustration in the drawings.)

With the construction above described I am enabled to fulfil every requirement imposed upon a crown block in well drilling service. There is ample provision for adjustment of the various sheaves to correct position on the derrick crown; and there is ample provision for all lines likely to be required. Should more casing lines be required than is provided for by the sheaves 20, I may extend my block by duplication, merely duplicating one or more of the longitudinal members and the sheaves 20. I have provided for dust proof construction and for continuous and efficient oiling of the different bearings. These provisions are of a very practical nature; in an ordinary crown block as now used it is necessary that frequent attendance be had.

Having described my invention, I claim:

A crown block, comprising in combination, four horizontal parallel spaced beams, two casing line sheaves in each of the spaces adjacent the outermost beams arranged one near each end of said beams, bearing blocks 10^a for said sheaves on the beams on each side of the said spaces, said bearing blocks being adjustable longitudinally on the beams, a sand line sheave at one end of the space between the two inner beams, bearing blocks 10^a for said sheave on the two inner beams, said bearing blocks being independent of the first mentioned bearing blocks, a drilling line sheave between the two inner beams near their other ends and near the casing 110 line sheaves at that end, and bearing blocks for the drilling line sheave on the two inner beams, said blocks connected with the adjacent bearing blocks for the casing line sheaves, so that when the said adjacent casing line sheaves and drilling line sheave are adjusted longitudinally of the beams they maintain fixed relation to each other.

In witness that I claim the foregoing I have hereunto subscribed my name this 18th 120 day of October 1912.

RICHARD E. KLINE.
